UNITED STATES PATENT OFFICE.

CECIL FEATHERSTONE HAMMOND AND WILLIAM SHACKLETON, OF LONDON,
ENGLAND.

APPARATUS FOR DYEING OR WASHING TEXTILES.

Application filed July 28, 1928, Serial No. 295,988, and in Great Britain April 13, 1927.

This invention relates to apparatus for effecting liquid treatments of textile materials, such as articles of clothing, pieces of fabric and so on. The said liquid treatments 5 include dyeing, washing and like operations. In apparatus for these purposes as heretofore employed, the dye or wash liquor was heated by passing steam into it, and agitation of the liquor was obtained by the introduction of 10 jets of air directed so as to produce a circulation of the liquor. A disadvantage incidental to the introduction of steam in the manner aforesaid is that condensation of such steam brings about a gradual dilution of the treatment liquor which is very troublesome particularly in the case of dye baths.

The principal object of this invention is to provide what may be called a self-contained apparatus adapted for performing treatments with liquids unaccompanied by the drawbacks heretofore experienced. The term "self-contained" is used in the sense that the processes can be performed without the necessity for providing outside sources of steam 25 and compressed air supplies. In the specification of our application Ser. No. 133,683, the employment of submerged combustion is described and claimed for the heating, elevating and circulating of liquids, the performance being distinguished by the introduction of the products of combustion from the submerged flame into a column of the liquid in an enclosure having an inlet and outlet, which column became heated and 30 aerated thereby, the result being a heating and simultaneous raising of the liquid according to the air-lift principle. The principal object of the present invention is capable of realization by an adaptation of the method 35 of simultaneous heating and air-lifting of the treatment liquid.

According to this invention, a submerged burner is employed for simultaneously heating and aerating a localized portion of the 45 liquid of the treatment bath, such heated and aerated liquid being then elevated according to the air-lift principle and subsequently utilized in such a manner as to promote a circulation of the body of liquid in the treatment 50 bath.

A desirably compact and self-contained arrangement is one in which a submersible burner operates in a relatively isolated part of the bath, the liquid in such isolated part becoming heated and aerated and thereupon 55 forcibly delivered directly into the body of the bath with such guidance as to promote a vigorous circulation within the bath. It is advantageous to displace the heated and aerated liquid by means of liquid admitted 60 from the body of bath liquid to a secondary circulation duct, the admission to such duct being at a distance from the nozzle of the burner and of such a nature as to keep the duct filled without setting up such suction 65 effect on materials in the bath as would tend to hold the latter or retard their free movement.

In order to enable the invention to be readily understood, reference is made to the accompanying drawings illustrating suitable 70 constructions of apparatus for the carrying out of the processes, in which drawings:

Figure 1 is a central vertical section of an apparatus for the performance of the process 75 by the direct application of the gases of submerged combustion to the liquor of the bath.

Figure 2 is a section of the top part of the apparatus, the section being taken at right angles to the section in Figure 1.

Figure 3 in its lower part is a section taken about on the line III—III of Figure 1, and in its upper part is a section taken about on the line III^a—III^a of Figure 1.

Figure 4 is an elevation to a greatly reduced scale of the complete apparatus as viewed from the same position as that from which Figure 1 is viewed.

Figure 5 is an elevation viewing the apparatus from the right hand side of Figure 4 85 but with the lid of the bath in its raised position.

Figure 6 is a plan of Figure 4.

Figure 7 is a central vertical section of a modified construction of apparatus.

Figure 8 is an irregular section of a modified construction, and Figures 9 to 11 are sectional plan views of a detail shown in Figure 8.

Referring to Figures 1 to 6, *a* is the vat or 100

treatment chamber which, as seen from Figure 3, is more or less rectangular in horizontal section but which, in vertical cross section, and as seen in Figure 1, comprises an internal wall *b* which is of curved formation to conform with, for example, an arc of a circle or of an ellipse. This curved wall *b* is of hollow formation either wholly or in parts so as to provide a duct or ducts *c* without its thickness, the said duct or ducts communicating at one end of the arc with a so-called sump *d*. The latter is situated at the foot of a flat rear wall of the vat and may have the cylindrical formation shown by Figures 1 and 3. The lower portion of the rear wall may be thickened as illustrated to permit of forming the sump within its thickness and to permit also of the formation of a flat chamber *e* at each side of the sump and communicating therewith, as is clear from the upper half of Figure 3. The duct *c* may open into the flat chambers *e* as well as into the sump *d*. The top of the sump is perforated to permit of the passage of the nozzle of a depending burner *f* which is of the submersible type capable of maintaining combustion although its nozzle is submerged in the liquid contained in the sump *d*. The top part of the thickened wall covering the chambers *e* is provided with perforations or with elongated ports *g* Figure 3 of slot formation, for a purpose to be described. The vat *a* is advantageously moulded from suitable clay or plastic material so as to be acid-resistant or non-corrodible, and the hole *d'* beneath the sump *d* is plugged as it is simply intended for facilitating the coring out of the sump and the perforation in the top of the latter. The upper portion of the rear flat wall is formed with an inwardly projecting deflector *h* and the top edge of the wall *b* has a formation *h'*, these parts *h* *h'* producing a throat at *j* and a flared mouth at *k*. The deflector *h* projecting from the flat wall is wider than the part *h'* and is perforated for the passage of the cylindrical body of the burner *f*. The vat *a* is closed by a main cover or cover frame *l* having an opening in the middle which is closed by a lid *m*. The cover *l* is formed with a depending flange *l'* which takes over the top of the vat, and is channeled to receive a rubber or other packing strip *n* which seats upon the top edge of the vat. The underside of the cover *l* is, moreover, channeled or hollowed out at *o* for a purpose to be described, and is formed with a perforation for the passage of the burner *f*. The burner *f* is supported by a perforated triangular foot piece *p* which engages beneath a shoulder on the burner as seen in the top left hand portion of Figure 1 and is disposed a short distance from the rear wall of the vat so that the burner is cooled by the bath liquor surrounding it. The foot piece *p* rests upon and is bolted down on to the cover *l*, as shown, the depending burner passing through the appropriate holes in the cover *l*, rim *h*, and top of the sump *d*. It will be observed that the burner also passes through a spacer sleeve *q* 70 and a packing ring *r*, the parts being dimensioned so that when the cover *l* is pressed down tightly, the sleeve *q* presses upon the ring *r* to cause the latter to make a fluid-tight packing around the burner tube. Any suitable means may be provided for tightening the cover *l* down on the vat *a* but they are omitted from the drawing for sake of clearness. It is only necessary to observe that when the vat and cover are made of brittle 80 material, the tightening means must include some resilient or limiting means for preventing over-tightening of the cover *l* which might cause breakage. The lid *m* is thickened around its rim and is fitted therein with a 85 packing strip *s* for seating upon the cover *l*. In the middle of its upper surface the lid *m* is formed with an upstanding lug *t* in which are two perforations one above the other. The lower one is for the reception of a pin *v* carried in the free end or fork of a lever arm *u* pivotally mounted at one side of the vat, and the upper one is for the reception of a pin *w* which engages between pairs of 90 upwardly directed lugs *x* on such forked free end of the lever arm *u*. The pivot spindle *y* of the lever arm *u* is supported in suitable bearings *y'* Figure 6 and is extended beyond the bearing at the right hand side of Figures 1 and 6 so as to be available 95 for the mounting of a hub or sleeve *z* formed with arms 1 at diametrically opposite points. For sake of clearness these two arms are shown in Figure 1 as being in the plane of the paper although the lid *m* is shown closed 100 but they should be in a position perpendicular to the paper when the lid is closed, as will be clear after a description of Figures 4 to 6. The arms 1 serve for the attachment of a long arm 2, the rivets for such attachment being seen in Figure 6 and the rivet holes only being seen in the arms in Figure 1. The arm 2 carries a weight 3 which is mounted with guidance on the arm 2 so that it can slide to and fro along the length of such arm 2. It will be seen from Figures 5 and 6 that the arm 2 is extended beyond the pivot spindle *y* and it is of greater depth than the arms 1 so that the weight 3 can be moved by its handle 4 right along the arm 2 beyond 110 the pivot without being fouled by the arms 1. By comparing Figures 5 and 6 it will be apparent that when the weight 3 is moved to the end of the arm 2, the weight 3 will overbalance the weight of the lid *m* and will hold the latter in its closed condition down on the cover *l*. If the weight be caused to slide to the opposite or extended end of the arm 2 so that it arrives in the position seen 115 in Figure 5, it will operate to open, or assist 120 the opening of the cover *l*. The weight 3 is 125 formed with a slot 5 which receives a pin 6 130 which is held in the slot 5 by a spring 7.

to open, the lid *m* and to retain such lid in the opened position. A suitable stop at the inner end of the arm *2* prevents the weight from sliding off. It will be seen from Figure 5 2 that the lid *m* cannot turn about the pivot pin *v* during raising and lowering by the arm *u* owing to the engagement of the pin *w* between the lugs *x* on the arm *u*. The cover *l* is fitted with an outlet connection *5* for 10 gases of combustion and vapours, such outlet connection being in communication with the channel or hollow part *o* of the cover *l*. Also, there may be an aperture *6* in the cover for the insertion into the bath of a thermostat 15 device adapted for controlling the burner supply of fuel, or air, or both, in accordance with the temperature developed in the bath. Or means controlled by the pressure existing in the bath may be substituted for the 20 thermostat.

The curved wall part *b* is provided with perforations *7* for giving communication between the interior of the vat and the duct or ducts *c*. In the example illustrated in Figure 25 1, these perforations *7* are formed in the upper portion of the wall *b* and have a somewhat tangential direction, but it will be understood that such perforations may be formed in other portions of the wall and may 30 be given any suitable direction. A drainage hole *8* with plug or valve is formed in the bottom of the vat and communicates with the duct *c* and there may be perforations *9* communicating between the lowest point in the 35 vat and such duct so that all liquor may be drawn off from the vat when required.

In operation, the vat *a* is charged with a suitable treatment liquor up to say, the throat level at *j* and the lid *m* is opened by lifting 40 the arm *2* and shifting the weight *3* to the position seen in Figure 5. The articles or material to be treated are then introduced into the vat through the opening in the cover *l* the flared mouth *k* facilitating this introduction. The arm *2* and weight *3* are now operated to close down the lid *m*, the weight *3* operating to apply sufficient pressure to the 45 lid for causing its packing *s* to make a tight joint on the cover *l*. The burner *f* may be of 50 the construction shown in United States Patent No. 1,689,551, dated October 30, 1928, wherein means are disclosed for lighting the flame. The gases of combustion from the burner are delivered from the nozzle into the 55 liquor contained in the cylindrical sump *d* and become highly diffused therein, with the result that such liquor is efficiently heated and is also aerated by the gases so that the column of liquid in the sump is lightened. The 60 greater weight of the column of liquid in the duct *c* will thereupon cause displacement of the aerated liquid in the sump *d* so that such aerated liquid will pass laterally into the flat chambers *e* and will be delivered upwardly through the slots *g* in the form of jets. 65

The upward currents thus initiated meet the curved lower surface of the deflector part *h* and are deflected across the vat where they meet the curved or cylindrical surface of the wall *b* and thus acquire a circular motion 70 as indicated by the arrow heads on the diagram lines of flow and circulation in Figure 1. The circular motion of the currents produces a revolving motion of the body of liquid and causes the liquid to be positively 75 and uniformly active upon the material contained in the vat so that, if dyeing is being performed, the fabrics contained in the vat are uniformly treated. Some of the liquid in its revolution or circulation will 80 pass through the perforations *7* to keep the duct *c* full as will be apparent from Figure 1. The gases of combustion and any vapours produced by the heat will separate 85 from the liquid in the upper part of the vat and collect beneath the cover *l* and lid *m*. Such gas and vapours are conducted by the inverted channel *o* to the outlet *5* through 90 which they escape or are led to a suitable place of exhaust. When the treatment is finished, it is a very simple matter to open the lid *m*, remove the treated goods and introduce a fresh batch for treatment. The number of perforations *7*, or the perforated area, is made sufficiently large to render the velocity 95 of the inflow at the individual perforations as low as possible so that the materials undergoing treatment shall not be held against such perforations by the suction which would otherwise be effective for so holding such 100 materials and preventing or retarding their free movement in the vat.

It will be apparent that the construction described eliminates as far as possible any zones or pockets in which circulation cannot 105 take place. The slightly increased concentration of the bath liquor which may be due to evaporation may be advantageous in many processes in which a slightly increasing concentration during the progress of the process 110 is desirable, whereas a diminished concentration such as is produced by condensed steam may be very disadvantageous.

Naturally, the apparatus is capable of 115 modification in various ways, without departing from the invention. For example, it will be seen that the uprising aerated currents of liquid release their gases of aeration upon arriving at the top of the vat or vessel as hereinbefore described. Now if desired and as shown in Figure 7, the sump or enclosure 10 in which the nozzle of the burner 11 is disposed might be connected with a rising pipe 12 which would be arranged to deliver the 120 heated and aerated liquor into a tank or container 13 situated above the level of the top of the vat or vessel 14. In this case, the elevated liquor would release its gases of aeration in the tank or container 13 and the latter would return such liquor through a suit- 125 130

able downtake 15 which would direct the returned liquor through the passage 16 into the vat or vessel in such a manner as would be best calculated to promote circulation therein. Vat liquor would be returned through perforations 17 in the vat into a passage 18 communicating with a connection 19, leading to the sump 10. Also, the sump *d* 5 may be differently disposed and may have 10 a central situation instead of the side wall situation illustrated.

According to the modification shown in Figures 8 to 11 the liquid which is heated and aerated by the products of combustion from the burner 20 is delivered through a rising pipe 21 to an elevated tank or container 22. The vat 23 communicates with the tank 22 through a downtake pipe 24 and a passage 25 or 26, one of these passages being used for 15 the delivery and the other for the return of liquid from the vat to the sump or enclosure 27, as determined by the position of a ported valve 28 which is mounted on a spindle 29 and is rotatable to any one of three different 20 positions by means of a lever arm 30. The three different positions are illustrated in Figures 9, 10 and 11.

In Figure 9 the valve permits flow of liquid from the tank 22, through pipe 24, valve port 28^a and passage 25 to a central perforated pipe 31 from which the liquid is directed into the body of the bath contained in the vat 23. Liquid returns from the vat 23 through the passage 26, valve port 28^b to the sump 27. 30 Thus the flow of liquid in the vat is in the direction shown by the flow lines of Figure 8.

In order to obtain a reversal of the direction of flow in the vat, the valve 26 is rotated to the position shown in Figure 10, in which case liquid flows from the downtake pipe 24, through valve port 28^a and passage 26, into the vat, whilst the liquid is returned to the sump through the perforated pipe 31, passage 25 and valve port 28^b.

45 In Figure 11 the valve is in such position that the vat 23 is by-passed and the liquid now passes down the pipe 24 through the valve port 28^a directly to the sump or enclosure 27.

50 In the event of the thermostat above referred to being operative for controlling the admission of additional air to the burner, it is possible to vary the rate of heating of the liquor whilst maintaining constant the vigour of the agitation or circulation of the bath, and this is of practical importance in some treatments of which dyeing is a favourable example. Thus, the invention not only avoids the dilution and other drawbacks attendant on the use of steam but it also avoids the necessity for supplying air under pressure to produce agitation. If pressure air is employed, such air is wholly or partly used first of all for supporting combustion in the burn-

er, so that in this respect an economy is effected.

65 In treatment processes in which it may be necessary to maintain a high temperature, the vat or vessel may be jacketed and a liquid having a very high boiling point may be heated and circulated through such jacket by 70 means of a submersible burner.

We claim:—

1. Liquid treatment apparatus comprising a vat adapted for the circulation therein of a 75 body of treatment liquid; a chamber adapted for isolating a portion of such body of liquid, down-take and up-take communications between said vat and said chamber, burner supporting means, a submersible burner adapted 80 for being supported by said means with its nozzle submerged in the liquid in said chamber, and directive means adapted for circulating within the vat the liquid air-lifted by said burner.

85 2. Liquid treatment apparatus, comprising a vessel and ducts constituting a circulatory system, a burner supported with its nozzle submerged in one of said ducts and adapted for air-lifting liquid in said duct, and directive delivery means on said duct adapted for directing delivery of such liquid into said vessel for the circulation of the body of liquid therein.

90 3. Liquid treatment apparatus comprising 95 a vessel, downtake and uptake ducts communicating with said vessel and with one another, a burner chamber in connection with said uptake duct, a submersible burner supported in said chamber with its nozzle submerged in liquid normally contained in said uptake duct, and delivery nozzle means in association with the upper end of said uptake duct, said nozzle means being directive for circulating within said vessel the liquid air-lifted by said burner in the uptake duct.

100 4. Liquid treatment apparatus comprising a vessel adapted for containing a body of liquid and forming part of a circulatory system, an enclosure formed in said circulatory system and having directive delivery communication with said vessel, a submersible burner supported in said enclosure and adapted to heat and aerate the liquid column within said enclosure, and a duct formed with inclined 110 perforations adapted to establish downtake communication between said vessel and said enclosure.

115 5. Liquid treatment apparatus comprising a vessel having a curved interior and forming part of a circulatory system, an enclosure formed in said circulatory system, a submersible burner supported in said enclosure and adapted to heat and aerate the liquid column contained within said column, and a duct embodied within the thickness of the wall of said vessel and forming part of said circulatory system, said duct being adapted to deliver 120 125

heated liquid from said enclosure into said vessel with circumferential guidance.

6. Liquid treatment apparatus comprising a vessel adapted for containing a body of liquid,

5 uid, a sump formed in the lower part of said vessel, a burner supported with its nozzle submerged in the liquid contained in said sump

and ducts connected between the sump and the vessel and adapted for carrying the liquid put into circulation by the air-lift effect due to said burner when in operation.

CECIL FEATHERSTONE HAMMOND,
WILLIAM SHACKLETON.
